horizontally), or from open to closed position. The end 50 will be pivoted about an axis defined by groove 52 during such movement of the cover in the cut-out portion 64 of cross bar 42.

Referring to Fig. 7, the manner in which the cover 18 is adapted to be held in its open position may be seen. The groove 52 in the base 42 is preferably set substantially toward the bracket arm 32 adjacent abutment flange 58, although any position for the groove may be provided which serves to place the spring 48 under tension stress and thereby bias abutment flange 58 laterally in the direction of the bracket arm 32. Thus the spring will normally hold the extension 26 and its abutment flange 58 against the bracket arm 32 when the cover is in the seated position of Fig. 3. However, when the cover is lifted so that flange 58 disengages arm 32, the tension of spring 48 will force flange 58 behind bracket arm 32 and thereby lock it and the cover 18 against the downward bias of the spring.

In operation, therefore, the cover 18 may be lifted by means of handle 24 from the annular flange 14 so that when it passes a position, for example, substantially beyond 90° relative to base plate 12 as seen in Fig. 6 sufficient for flange 58 to clear bracket arm 32, the tension of the spring 48 will automatically move it to the right 25 for locking engagement with the bracket 32 as stated. Likewise, when it is desired to seat the cover 18 on the flange again, the operator need only press the finger tab 60 to move the cover 18 leftward, suitable indicia being preferably inscribed on the cover to indicate the correct 30 direction of movement. When the abutment flange 58 has moved laterally past the bracket arm 32, the torsion force of the spring 48, which will be augmented by upward movement of end 54 against hinge extension 26 in response to increased tension in the spring, will cause the 35 cover to seat against flange 14. The hinge extension 26 will then be guided throughout by the abutting relation of bracket arm 32 and abutment flange 58 so that annular flange 20 will be held in precise registration with flange 14 during seating of the cover.

The outlet 10 can be easily installed by inserting screws (not shown) through openings 66 and 68 defined by the base 12. The materials of which the outlet is constructed may be conventional, the base plate 12 being preferably of brass while the cover 18 is a zinc die casting, and the 45 bracket 34 is steel sheet. The pivot bar 28 is preferably a tubular aluminum rivet while stainless steel is used for the helical spring 48. The gasket 22 may be made of thick sponge rubber.

Because there are relatively few parts and these are in permanently assembled condition, the device is not subject to wear or mechanical breakdown. Furthermore, the simplicity of the construction is such that variations in manufacturing tolerances will not affect its operation while the ease with which the cover can be moved from open to closed position, or from closed into automatically locked open position, insures that it can be used in ordinary household as well as commercial application 10 without difficulty.

Although I have described my invention with respect to certain principles and details in a specific embodiment thereof, it will be understood by those skilled in the art that these may be varied in accordance with the spirit and scope of the hereunto appended claim.

I claim:

An all weather electrical outlet comprising a base plate defining an upstanding annular flange providing an outlet opening, a cover having a flat seating surface to seat on said annular flange, a hinge extension on said cover having parallel side edges and an inner surface which is parallel to the seating surface, a bracket secured to said base plate having a pair of upstanding parallel bracket arms; a pivot bar secured by said bracket arms in parallel spaced relation to said base plate, a pair of depending flanges on said hinge extension defining openings for receiving said pivot bar, one of said flanges being disposed inwardly a predetermined distance from the adjacent side edge of said hinge extension to define a cover hinge extension abutment flange, and a spring helically disposed on said pivot bar having one end secured to said bracket and the other end secured to said cover a distance from said first end to exert tension stress on said spring to move said cover and abutment flange laterally with the inner surface of the abutment flange contacting the rear surface of one of the bracket arms wherein the cover is locked in open position when said cover is pivoted upwardly a predetermined extent, said spring further being under torsion stress to bias said cover downwardly upon said annular flange when said cover and abutment flange are moved laterally in the opposite direction past said bracket arm rear surface.
